[57] CLAIM

The ornamental design for a snack tray or the like, as shown and described.

DESCRIPTION

FIG. 1 is a top plan view of a snack tray or the like showing my new design.

FIG. 2 is a side elevational view, with the side opposite that shown being a mirror image thereof.

FIG. 3 is a bottom plan view.

FIG. 4 is a sectional view in elevation taken along line 4—4 of FIG. 1.

FIG. 5 is an end elevational view as seen from the right side of FIG. 2.

FIG. 6 is an enlarged fragmental sectional view in elevation of an edge portion shown in FIG. 4.
